(57) **CLAIM**

The ornamental design for a surgical guide tray, as shown and described.

DESCRIPTION

FIG. 1 is a perspective, exploded view of a surgical guide tray, showing our new design;

FIG. 2 is a front elevation view of the surgical guide tray illustrated in FIG. 1;

FIG. 3 is a rear elevation view of the surgical guide tray illustrated in FIG. 1;

FIG. 4 is a right elevation view of the surgical guide tray illustrated in FIG. 1;

FIG. 5 is a left elevation view of the surgical guide tray illustrated in FIG. 1;

FIG. 6 is a top plan view of the surgical guide tray illustrated in FIG. 1;

FIG. 7 is a bottom plan view of the surgical guide tray illustrated in FIG. 1;

FIG. 8 is a perspective, assembled view of the surgical guide tray illustrated in FIG. 1;

FIG. 9 is a front elevation view of the surgical guide tray illustrated in FIG. 8;

FIG. 10 is a rear elevation view of the surgical guide tray illustrated in FIG. 8;

FIG. 11 is a right elevation view of the surgical guide tray illustrated in FIG. 8;

FIG. 12 is a left elevation view of the surgical guide tray illustrated in FIG. 8;

FIG. 13 is a top plan view of the surgical guide tray illustrated in FIG. 8; and,

FIG. 14 is a bottom plan view of the surgical guide tray illustrated in FIG. 8.

In the drawings, the broken lines depict environmental subject matter only and form no part of the claimed design.
